UNITED STATES PATENT OFFICE

GEORG VON ARCO, OF BERLIN, GERMANY, ASSIGNOR TO GESELLSCHAFT FÜR DRAHTLOSE TELEGRAPHIE M. B. H., OF BERLIN, S. W. 11, GERMANY, A CORPORATION OF GERMANY.

SPEED GOVERNOR.

Application filed June 28, 1924, Serial No. 723,064, and in Germany July 2, 1923.

My invention relates to means for automatically maintaining the speed of a rotating machine approximately constant. It has for its object to provide a governor which 5 will be very sensitive to speed variation and keep the speed within very narrow limits as this is particularly desirable in high speed alternators such as used in radio.

Other objects will be apparent to those 10 skilled in the art from the following specification and claims when considered with the accompanying drawing, in which the single figure represents an embodiment of my invention.

15 The arrangement described in the following is known as a governor of the speed of rotation of a machine.

A mechanical system consisting of a spring and a weight is arranged on a turn-table, 20 rotating about a horizontal axis in such a way that the centrifugal force of the mass is balanced by the force of the spring for a certain critical speed of rotation. For this speed the mechanical oscillating system is 25 in an unstable equilibrium. The equilibrium between mass and spring is disturbed by the slightest alteration of the speed and the centrifugal force.

The force of gravity is added to and sub- 30 tracted from the centrifugal force at every revolution, so that the mass carries out an oscillation of a certain amplitude at every revolution.

A disadvantage of this very sensitive regulating system is that the mass as well as the 35 force of the spring must be altered, if the condition of unstable equilibrium is to be newly adjusted for another desired speed of rotation. It is very difficult in practice to 40 alter the critical speed of rotation by adjusting the governor itself. Therefore, it is remedied by driving the governor thru variable gearing by the machine, the speed of which is to be controlled.

45 The purpose of an invention disclosed in German application T. 27,816 I/60 and in United States application S. N. 716,532 filed May 29, 1924, was to remove this difficulty by regulating the governor itself. The principle of the invention was that the whole 50 mass of the oscillating system is divided into two parts, one of which is subjected to the centrifugal force and the other not. Therefore, this second part can be made larger

and the gravity thus made more efficient, so 55 that at every revolution of the turntable a sufficient working force is obtained even when there is a considerable friction between contacts.

The purpose of the present invention is 60 to provide an arrangement whereby the operation of the governor is controlled, not by centrifugal force and the force of gravity, but by centrifugal force and the force of an artificial field, as a magnetic field. 65

The arrangement may also be such that the added artificial field acts together with gravity or, as stated, the artificial field may act alone. This case occurs, for instance, if the axis of revolution of the governor is 70 vertical.

The invention will be better understood from the following description taken in connection with the drawing in which:

Fig. 1 is a plan view of the governor. 75

The drawing shows the invention in its simplest form and diagrammatically. Two spring-plates B_1 and B_2 , one of which is adapted to coact with a terminal C , are mounted on the turntable A , which, in turn, 80 may be mounted on an horizontal or vertical axis which is operatively connected to the rotating element of the machine it is desired to govern. The two spring-plates are connected by the rod D and the weight F is 85 arranged in the middle of the rod, exactly in the axis of revolution.

The resilience of the spring-plates B_1 and B_2 between the places where they are fixed to the turntable A and the places where the 90 rod D is fixed, supplies the spring action necessary to resist the centrifugal force of mass E . Terminal C is also mounted on turntable A . Contact is made and broken between terminal C and spring-plate B_1 for 95 different periods of time depending on the speed of rotation as will be pointed out below more in detail. The making and breaking of this contact serves to operate any well-known devices for regulating the speed of the machine and may also serve to operate a device (not shown) for stopping the machine if the speed becomes either abnormally high or low. 100

The additional weight E , smaller than F , 105 is mounted on rod D between plate B_1 and weight F . Weight F exerts just enough centrifugal force when the machine is run-

ning at the desired speed to balance the force exerted by spring-plates B_1 and B_2 . When the machine is running under this condition contact between plate B_1 and terminal C 5 will be open and closed every revolution due to the force of the artificial field and the force of gravity on mass F and mass E if the axis of revolution of the governor is horizontal, and due to the force of the artificial field alone if the axis of revolution is 10 vertical.

The artificial field may be due to an electromagnet M arranged so as to exert force on the governor principally upon the masses 15 E and F which will be made of magnetic material. The battery G and rheostat H is provided to vary the magnetic force exerted by the magnet upon the masses E and F. The chief advantage of this improvement is 20 that by adjusting the amount of current thru the winding of the magnet M, the strength of the field is also adjusted and it is thereby possible to adjust the sensitiveness and range of regulation of the governor 25 while the machine is running.

It is also possible to use, not a constant field, but a field which is periodically altered in accordance with the frequency or corresponding speed of rotation.

30 Thus it will easily be seen that if the machine speeds up above desired speed the centrifugal force of weight E will overcome the spring action of plates B_1 and B_2 and the contact between plate B_1 and terminal C 35 will remain closed longer than when running at desired speed. On the other hand, if the machine speed decreases from desired speed, the spring action of spring-plates B_1 and B_2 will overcome the centrifugal force 40 of weight E and the contact between plate B_1 and terminal C will remain open longer than when running at desired speed.

It will easily be seen by those skilled in the art that change of relative periods of 45 open and closed position of the contacts can control the speed of the machine in conjunc-

tion with any of the well-known devices in the art.

Having disclosed the principle of my invention, various modifications will be apparent to those skilled in the art. My invention, therefore, is not limited to the specific disclosure, but only by the scope of the following claims:

1. A speed control device comprising a 55 rotatable member, a radial member resiliently mounted on said rotatable member, centrifugal means associated with said radial member for making and breaking an electrical circuit, and variable magnetic 60 means to alternately aid and oppose the action of said centrifugal means.

2. A speed-control device comprising a rotatable member, a radial member resiliently mounted on said first mentioned member, means governed by the speed of rotation of the rotatable member to close an electrical circuit, and variable magnetic means to alternately aid and oppose the action of 65 said last mentioned means.

3. A speed control device comprising a rotatable member, a radial member resiliently mounted on said rotatable member, centrifugal means associated with said radial member for making and breaking an electrical circuit, and magnetic means to alternately and variably aid and oppose the action of said centrifugal means.

4. The arrangement for controlling the speed of a rotary machine by the relative length of the closed and open periods in a circuit, comprising a rotary member attached to said machine and adapted to rotate therewith, a magnetic mass resiliently mounted on said member and adapted to oscillate relative thereto, contacts adapted to be closed by the oscillation of said mass and stationary variable magnetic means for affecting the magnetic mass and altering the relative length of the open and closed periods of said contacts.

GEORG von ARCO.
